United States Patent Office

Des. 181,287
Patented Oct. 29, 1957

181,287

LAMP POST

Otto Harrison Gilfry, Buena Park, Calif.

Application January 4, 1957, Serial No. 44,404

Term of patent 14 years

(Cl. D48—31)

I claim:

The ornamental design for a lamp post, as shown.
